ARCHIBALD T. SAMPSON, OF LYNN, MASSACHUSETTS, ASSIGNOR TO SAMPSON AXCESS SYSTEM, INC., OF LYNN, MASSACHUSETTS, A CORPORATION OF MASSACHUSETTS.

PIPE-CUTTING APPARATUS.

1,412,220.

Specification of Letters Patent. Patented Apr. 11, 1922.

Application filed December 16, 1919. Serial No. 345,284.

To all whom it may concern:

Be it known that I, ARCHIBALD T. SAMPSON, a citizen of the United States, and resident of Lynn, in the county of Essex and 5 State of Massachusetts, have invented an Improvement in Pipe-Cutting Apparatus, of which the following description, in connection with the accompanying drawings, is a specification, like letters on the drawings 10 representing like parts.

My present invention relates to cutting apparatus, and more particularly to portable cutting apparatus adapted to cut a plurality of slots or openings in a metal pipe 15 or conduit.

In my various inventions upon an improved and novel system of electrical construction and installation, partly explained in my copending application, Serial No. 20 166,813, filed May 7, 1917, one of the important features consists in the method of cutting partially through a metal pipe or conduit without injury to the electric wires therein, and even when the pipe or conduit 25 is already in place in a building or other structure. In the development of my improved and novel system, above referred to, I have devised apparatus for performing the above-cutting operation, and have illustrated and claimed such an apparatus in my 30 prior copending application, Serial No. 318,036, filed August 16, 1919. My present invention relates to the same class of apparatus as that described and claimed in the 35 last mentioned application, and is an improvement thereon.

In my copending application, Serial No. 318,036, filed Aug. 16, 1919, I have described and claimed a cutting apparatus for cutting 40 a plurality of parallel slots simultaneously transversely of a pipe or conduit, and the invention described and claimed in the present application is capable of conjoint use therewith.

In carrying out my invention, I provide 45 means for slinging or hanging the apparatus from a pipe or conduit, preparatory to clamping such apparatus in position on the pipe or conduit. Clamping means are provided, and as it is always desirable, and sometimes essential, that slots be cut in a 50 pipe or conduit located in a corner, I have arranged the clamping means in such a position relative to the cutting means, that a 55 slot or slots can be cut in the pipe or con-

duit so situated. The pair of parallelly arranged slots are cut simultaneously, and I provide a pair of rotatable cutters for this purpose, means being also provided for rotating the cutters continuously or intermittently. Further, I provide means for yieldingly holding the cutters in cutting position, the tension of said means being adjustable. 60

Except when the cutting operation is actually being performed, I provide means for 65 moving the cutters outwardly from each other, and from the pipe or conduit.

The principal object of my invention therefore, is an improved apparatus for cutting a plurality of parallel slots in a pipe 70 or conduit and longitudinally thereof.

Another object is to provide means for preventing the cutters from injuring the wires or conductors encased in the pipe or conduit. 75

Still another object is the provision of means for yieldingly holding the cutters in operative position.

Other objects and novel features of the construction and arrangement of parts will 80 appear as the description of the invention progresses.

In the accompanying drawings, illustrating the preferred embodiment of my invention, 85

Fig. 7 is a view, partly in section, on the line 7—7 of Fig. 1,

Fig. 8 is a detail, showing the manner of connecting the operating handle to the 100 driving shaft.

Fig. 9 is a sectional view, taken on the line 9—9 of Fig. 8,

Fig. 10 is a detail of the equalizing means employed in connection with the clamping 105 jaws, and

Figs. 11 and 12 are details, showing the application of one of the cutters to pipes of small and large diameters, respectively.

Referring to the drawings, 10 and 11 des- 110

gnate end members, spaced apart by bars 12 and 13, which bars are preferably cast integral with the end members and form ways or guides for the cutting apparatus, 5 to be hereinafter described. Referring particularly to Fig. 7, which shows one of the end members 11, in end elevation, it will be noted that such member has lugs or ears 14 and 15, formed integral therewith, and extending laterally therefrom. These lugs or ears 14 and 15 are perforated at 16 and 17 respectively, parallel to the bars 12 and 13. In each of the apertures 16 and 17 are placed shafts or rods 18 and 19, which are held in 15 place by pins 20. These shafts or rods 18 and 19 extend outwardly on either side of the lugs or ears 14 and 15 respectively, and provide bearings for the clamps 21 and 22 respectively. The clamps 21 and 22 extend 20 upwardly on either side of and substantially parallel to the end member 11. The top of the end member is slotted at 23, in a direction parallel to the bars 12 and 13 and is provided with a perforation 24 at right angles to and in alignment with the lugs or ears 14 and 15. The clamps 21 and 22 are each provided with a perforation 25 in 25 alignment with the perforation 24 in the top of the end member 11. As but one such perforation 25 is illustrated, that in the clamp 22, in Fig. 7, and as the clamps 21 and 22 are similar in construction, only such clamp 22 will be referred to in describing such construction, it being understood however, that 30 such description applies also to clamp 21. The clamp 22 comprises side walls 26 and 27 tied together, top and bottom, by the jaws 28 and web 29 respectively, said jaws and web being joined together by a central web 30, also extending between and uniting the 35 side walls. The side walls extend below the web 29 and are provided with aligned holes of approximately the same diameter as the shaft or rod 19, the side walls straddling the lug or ear and preventing sidewise movement of the clamp. The face 31 of the jaw 28 bears such a relation to the perforations in the lower end of the side walls 26 and 27 that the cooperating clamps 21 and 22 will 40 hold pipe or conduit of different diameters in predetermined position with respect to the cutting apparatus to be hereinafter described. Further, the length of the face 31 is greater than the length of the face 152 45 and the angle made by the faces 31 and 152, while shown as slightly less than a right angle, is preferably a right angle. By referring to Fig. 7 it will be noted that the face 31 is substantially vertically over the 50 pivot point of the jaw 22, and that movement of the jaw to the right, about its pivot point, will cause a lowering of the face 31, and therefore, a corresponding movement of the face 152. As the movement of the 55 jaw 21 is simultaneous with, but in the op-

posite direction to the jaw 22, it will be apparent that the jaws will open or close, to receive larger or smaller pipe or conduit. Also the above described movement of the jaws positions the pipe or conduit, regardless of diameter thereof, in predetermined position with relation to the cutters, and insures that a slot for the pipe will be made by said cutters, the size of the slot being predetermined for each diameter of pipe. 70 75

Extending through the perforation 24 and on each side of the upper end of the member 11 is a rod 32, provided on its ends with right and left hand threads 33 and 34 respectively. This rod 32 also passes through 80 a collar 35 which fits into the slot 23 and is fastened to the rod by a pin 36 to prevent endwise movement of such rod. The perforation 25 is considerably greater in diameter than the rod 32 to allow free pivotal movement of the clamp 22 on the bearing rod 19 within desired limits, and the metal of the central web 30 is thickened adjacent such perforation 25, and such thickened portion is rounded, as shown at 37 in 90 Fig. 7. A nut 38, one for each threaded end 33 and 34, has its inner face rounded to conform with the rounded face 37 above described. The intermediate portion 39 of the nut 38 is reduced, as shown, to fit between the depending side members 40 and 41 of the guide 42, which guide is pivotally mounted between the side plates 26 and 27 by the pin 43. A horizontal member 44 of the guide 42 bears on the top of the central 100 web 30 adjacent the meeting point of the web and the jaws 28. The outer faces of the depending side members 40 and 41 of the guide 42 are rounded in substantially the same manner as the thickened portion 105 of the central web 30, and bears against the end of nut 38. A handle 45 is attached at one end of the rod 32 and by means of which said rod may be turned to open or close the jaws 28 of the cooperating clamps 110 21 and 22.

The end member 10 is similar to the end member 11, and carries cooperating jaws 46 and 47 and operating means therefor, similar in all respects to the jaws 21 and 22 and the operating means just described. In addition, the end member 10 is provided with a pair of lugs or ears 146, formed integral therewith, in which is pivotally mounted, by means of a pin 147, the hook 48, and by means of which the entire apparatus may be suspended on a pipe or conduit, preparatory to adjusting the apparatus in position thereon.

Slidably mounted on the bars 12 and 13 for longitudinal movement is a carriage 49, comprising side members 50 and 51, held together in position on the bars 12 and 13 by a plurality of screws 52. The member 50 is provided with a V-slot 53, to engage with 125 130

the corresponding V-projection 54 on the bar 12. A gib 55 is placed between the bottom of the bar 12 and the main portion of the member 50. Rotatably mounted in the member 51 is the main driving shaft 56, said shaft extending beyond the member at each end. Fixed to the shaft 56, by the pin 57, is a gear 58 which meshes with a gear 59, of equal pitch and diameter, fixed to and rotatable with the shaft 60 parallel to the shaft 56 and mounted in the member 50.

Partially enclosing the gears 58 and 59 are casings 61 and 62 respectively, as clearly shown in Fig. 5.

15 A frame member 63, having a projecting arm 64 at one end and a projecting arm 65 near the other end, is provided with a hollow casing or cover 66 intermediate its ends and in alignment with the casing 62. Said frame member 63 is pivotally mounted on the shaft 56 by means of the projecting arms 64 and 65, the shaft 56 having a collar 67 formed integral therewith and engaging in an annular depression in the end of the 25 frame member 63 adjacent the projecting arm 64, while a screw 68 is provided for retaining the end of the frame member 63 onto the end of the shaft 56.

Extending outwardly, or upwardly, as 30 viewed in Fig. 1, from the frame member 63, is a flange 69 and through which and the frame member is rotatably mounted a shaft 70. This shaft 70 lies parallel to the shaft 56 and is reduced at its end to form a shoulder 97 and against which abuts a collar 74, the shoulder 97 providing means for spacing the collar 74 from the flange 69, as clearly shown in Fig. 11. The cutter 71 slips over the reduced end of the shaft 70

40 and the cutter 71 and collar 74 are clamped to the shaft by the washer 72 and nut 73. An angular circumferential cut is made in the collar 74, on the side adjacent the cutter 71, and on this cut away portion is rotatably

45 mounted the collar 151, the diameter of which is proportioned to the diameter of the cutter 71 and which, as clearly shown in Figs. 11 and 12, limits the depth of the cut in the pipe or conduit 136. It will be noted,

50 by a comparison of Figs. 11 and 12, that the collar 151 cooperates with the cutter 71 to vary the depth of the cut made, in accordance with the variation in the diameter of the pipe being worked upon. By this simple expedient, I am enabled to use a single

55 standard sized machine carrying a fixed diameter of cutter to cut slots in pipes of various diameters to the required depth for each diameter of pipe, and yet not deep enough to allow the cutter to come in contact with, and injure the wires or conductors that may be enclosed therein. Mounted on the shaft 70, intermediate the ends thereof, and in alignment with the gear 58 is a gear 75, 60 of a pitch equal to the pitch of the gear 58

and of any suitable diameter. This gear 75 is partially enclosed by the casing 66. The frame 63 is rotatable about the shaft 56 as a pivot, and it will be seen, from an inspection of Fig. 5, that the casings 62 and 66 act 70 to enclose the gears 58 and 75 in all positions of the frame 63, preventing the access of dust or other impurities to said gears, as well as preventing injury by the gears to the operator of the device. 75

Extending outwardly from the arms 64 and 65 are arms 76 and 77 respectively, these arms 76 and 77 being in alignment and providing bearings at their ends for a shaft 78 lying parallel to the shaft 56. Mounted 80 on the shaft 78, near each end thereof are sprockets 79 and 80, spacing collars 81 and 82 being placed between the ends of the sprockets 79 and 80 and the inside of the arms 76 and 77 respectively. The sprockets 85 are fastened to the shaft 78 by pins 83. The function of these sprockets will be explained hereinafter. Attached to the shaft 78 by the pin 84, and adjacent the sprocket 80, is a handle 85, by means of which the shaft 78, 90 and associated parts may be rotated. Also mounted on the shaft 78 and attached thereto by the pin 86, is a ratchet 87. Rotatably mounted on the shaft 78, between the ratchet 87 and sprocket 79, is a sleeve 88, 95 having an enlargement 89 at one end, and a handle 90 at the other end. Pivotally mounted on the handle 90 is a spring pressed plate 91 to which is pivotally mounted the pawl 92, engaging with the ratchet 87 to 100 hold the sleeve 88 in adjusted position on the shaft 78. A radially extending pin 93 on the enlargement 89 of the sleeve 88, engages with the slot 94 in a spring 95, which spring partially encircles the enlargement 105 89 and extends downwardly, as viewed in Fig. 6, where it is reinforced by the curved plate 96, which is folded back upon itself to engage with either side of the spring 95. The inside curve of the plate 96 engages 110 with frame 63 on the shaft 70. It will be apparent that rotation of the sleeve 88 will increase the tension of the spring 95, causing the plate 96 to force the shaft 70, and in this manner, cutter 71 and all other parts 115 associated with the shaft, inwardly, or toward the center line of the bar 12, as viewed in Fig. 2, and causing the cutter 71 to either deepen its cut, or be held with greater tension in its cut. 120

Pivotally mounted on the shaft 60 is a frame 98, which is practically identical with the frame 63. A shaft 99 rotatably mounted in projecting arms 100 and 101 of the frame 98, has rigidly attached thereto, by 125 pin 102, a gear 103, equal in pitch to the pitch of the gear 59 and equal in diameter to the gear 75 on the shaft 70. A casing 104 partially encloses gear 103, and co-operates with the casing 61 to encase the gears 59 130

and 103 and prevent injury thereto and thereby. The frame 98 has a flange 105 thereon, this flange being similar to the flange 69 on the frame 63. The shaft 99 extends through and beyond the flange 105 and a saw or cutter 109 is held on the shaft by the washer and nut 106 and 107 respectively. A collar 108, similar to the collar 151 on the flange 69, performs the same function with regard to the saw or cutter 109 that the collar 151 performs with regard to the saw or cutter 71. The shaft 99 is provided, intermediate its ends, with a collar 110, similar to the collar 97 on the shaft 70. Springs 111 and 112 located between the side members 50 and 51 and the collars, frames 63 and 98, respectively, tend to force the shafts 99 and 70, and associated parts, outwardly, as viewed in Figs. 5 and 6, 15 thus moving the saws or cutters 109 and 71 outwardly from each other. To further assist the springs 111 and 112 in moving the shafts 99 and 70 outwardly, I may provide a coil spring 113 passing around the 20 members 50 and 51, and having a hook at either end, one hook being attached to the open end of the casing 66 and the other hook to the open end of the casing 104, or any other suitable means to accomplish this 25 function.

On the frame 98, and in alignment with the sprockets 79 and 80 on the frame 63, are hooks, but one of which, 114, that in alignment with the sprocket 80, is shown. 30 (See Fig. 2). A sprocket chain 115 is fastened, one end to the hook 114 and the other end to the sprocket 80 while a similar sprocket chain 116 is attached, one end to the sprocket 79 and the other end to a hook corresponding 40 to the hook 114. It is evident that by operating the handle 85, the frames carrying the saws or cutters 71 and 109 are rotated to bring said cutters closer together, while by operating the handle 90, the tension of the 45 spring 95 may be varied according to the pressure it is desired to put on the cutters 71 and 109.

Rotatably mounted in suitable bearings in the end members 10 and 11 and lying 50 parallel to the bars 12 and 13, is a feed screw 117, which extends beyond the end member 11 and is provided with a handle 118, by means of which it may be rotated. This feed screw 117 engages with a female 55 threaded portion 119 in the member 50, and suitable means, as collars 120 and 121 on the feed screw, preventing end movement thereof, rotation of the feed screw causes a corresponding movement of the side members 60 50 and 51, and all parts carried thereby, along the bars 12 and 13.

Rotary motion is imparted to the cutters 71 and 109 by the gears 75 and 103 from the shaft 56, one end of which extends outward from the side members 50 and 51, as

shown in Fig. 1. Referring now to Figs. 1, 8 and 9, it will be noted that the extended end of the shaft 56 is provided with a circumferential groove 122. Over the extended end fits a sleeve 123, having fastened thereto, intermediate its ends, a ratchet 124. The sleeve 123 is keyed on the shaft 56 and a boss 125 is rotatable on the sleeve 123, being prevented from end movement on said sleeve by the ratchet 124 and an annular extension 126 on the end of the shaft. Rotatably mounted on the boss 125, by a screw 127, is a pawl 128, which is held in spring engagement with the ratchet 124 by a spring 129, riveted or otherwise secured 75 to the boss 125. The outer end of the boss 125 is provided with a dove-tailed slot 130 in which may slide the dove-tailed end 131 of the operating arm 132. The end of the arm is slotted at 133 and the end of this slot 80 is enlarged at 134 to provide a circular hole of a diameter slightly greater than the diameter of the shaft 56. The width of the slot 133 is slightly greater than the diameter of the bottom of the circumferential groove 90 122. The arm 132 is provided with a handle 134 by means of which it is operated. To assemble the operating means for the shaft 56, the sleeve 123 is slipped over the extended end of the shaft 56, the arm 132 95 being at this time in the dovetailed slot 130, with the circular enlargement 134 in alignment with the shaft. When the sleeve has been pushed onto the shaft 56 until the groove 122 is in alignment with the arm 100 132, said arm is forced to the right, as viewed in Figs. 1, 8 and 9, until the slot 133 engages the groove 122. When this occurs, a bolt 135, passing through the slot 133 and into the boss 125, is utilized to 105 hold the arm 132 in position. With this construction, I am enabled to rotate the shaft continuously by a rotary motion of the arm 132, or, and which is extremely important where it is necessary to operate 110 the device in a restricted space, as in a corner, I am enabled to rotate the shaft 56 intermittently by an oscillating motion of the arm 132.

Figs. 11 and 12 illustrate the position of 115 the cutters 71 or 109 when cutting slots in the smallest and largest pipes or conduits, respectively, that the device is capable of operating upon without adjustment. It will be noted that the angle made with a 120 perpendicular diameter, as viewed in Figs. 11 and 12, by a line extending from the center of the pipe to the point where the cutter breaks through the inner surface of the pipe is constant, regardless of the diameter of the pipe, and that therefore, the width between slots is the same regardless 125 of the diameter of the pipe. As hereinbefore mentioned, I attain this result by properly proportioning the angle the face 130

the clamp makes with the perpendicular drawn through the pivot point of such clamp.

The operation of my invention is as follows, it being assumed that it is desired to cut a pair of parallel slots in a pipe 136, in a manner similar to that described in my copending application Serial No. 166,813, above referred to, and that such pipe is arranged in a corner, that is, in the angle formed by the meeting of the ceiling and a wall of a building. The entire apparatus is hung on the pipe or conduit 136 by the hook 48 and the handles 45 utilized to open the jaws 28 of the clamps sufficiently to span the pipe. Also, the handle 90 is operated to reduce the tension in the spring 95 and allow the springs 111, 112 and 113 to swing the frames 63 and 98 on their axes to separate the cutters 71 and 109. The entire mechanism is swung on the pin 47 as a pivot and into the position shown in Fig. 3, where the handles 45 are operated to securely attach the device to the pipe 136 by means of the clamps, above described. This clamping operation automatically positions the cutting apparatus with respect to the pipe, so that the proper width between slots and the proper depth of slots will be automatically determined for the diameter of the pipe, regardless of what such diameter may be. Assuming now that the device has been properly positioned on the pipe, the handle 118 is used to rotate the feed screw 117 to move the side members 50 and 51 and all parts carried thereby, to bring the cutters 71 and 109 into position to start the cut. Handle 85 is now operated to rotate the sprockets 79 and 90 to draw the shafts 70 and 99 and thus the cutters 71 and 109 toward each other against the tension of the springs 111, 112, and 113, the cutters by this movement being brought into engagement with the pipe 136. The handle 90 is now operated to properly tension the spring 95 and yieldingly hold the cutters 71 and 109 against the pipe, the proper tension being maintained by the engagement of the ratchet 87 by the pawl 92. The shaft 56 is now rotated by means of the arm 132, and it having been assumed that the pipe 136 is located in a corner or angle, such rotation of the shaft 56 is intermittent and the motion of the arm a reciprocating one. Likewise the rotation of the cutters 71 and 109 by means of the gears 58, 75 and 59, 103 respectively, is intermittent. Only the arm 132 is operated until the cutters 71 and 109 have cut to such a depth that the collars 74 and 108 engage with the pipe, thus limiting the depth of cut, when the handle 118 is rotated simultaneously with the operation of the arm 132, to feed the cutters 71 and 109 along the pipe 136 and form the slots. After the proper length of slot has

been cut, the tension is removed from the spring 95, when the springs 111, 112 and 113 back the cutters 71 and 109 out of the slots, and the handles operated to release the mechanism from the pipe.

While I have necessarily described the preferred embodiment of my invention somewhat in detail, it is to be understood that I may vary the size, shape, and arrangement of parts within considerably wide limits without departing from the spirit of the invention.

From the above description it will be apparent that my improved cutting apparatus may be used to cut a slot longitudinally of a pipe, or a plurality of such slots simultaneously, and that when used to cut a plurality of slots, the space between said slots will vary in distance according to the diameter of the pipe operated on, this distance being predetermined. Again, the length of slot cut is predetermined absolutely by limiting devices forming part of the apparatus. The pressure with which the cutters are applied to the work may be varied between reasonably wide limits, the extreme limit being such that the cutters cannot be injured thereby. The apparatus is simple and rigid in construction, and as all the necessary adjustment required to be made—that of adjusting the pressure applied to the cutters—is such that no injury may result to the cutters, the apparatus may be successfully and efficiently operated by unskilled labor.

Having thus described my invention, what I claim as new and desire to secure by Letters Patent, is:

1. A machine of the class described adapted for forming parallel cuts simultaneously having, in combination, a guideway, supporting means at each end of said guideway, a support on said guideway, means for moving the support to and fro on the guideway, a pivotally mounted frame on the support, cutters rotatably mounted in said frame, and means for intermittently and continuously rotating said cutters.

2. A machine of the class described adapted for forming parallel cuts simultaneously having, in combination, a guideway, supporting means at each end of said guideway, a support on said guideway, means for moving the support to and fro on the guideway, a pair of frames pivotally mounted, one on each side of the support and movable toward and from each other, a cutter for each frame rotatably mounted thereon, and means normally tending to separate said frames and associated cutters.

3. A machine of the class described adapted for forming parallel cuts simultaneously having, in combination, a guideway, supporting means at each end of said guideway, a support on said guideway, means for mov-

6
ing the support to and fro on the guideway, a pair of frames pivotally mounted, one on each side of the support and movable towards and from each other, a cutter for each frame rotatably mounted therein, means normally tending to separate said frames and associated cutters, and means for yieldingly pressing said cutters toward each other.

4. A machine of the class described adapted for forming parallel cuts simultaneously having, in combination, a support, a pair of parallelly arranged shafts, one on each side of the support, a frame on each side of the support and pivotally mounted on the parallelly arranged shafts, a shaft rotatably mounted in each frame and parallelly arranged with respect to each other and with the first said parallelly arranged shafts, a cutter mounted on each of the shafts in the frame, and means for rotating said cutters at the same speed and in opposite directions.

5. A machine of the class described adapted for forming parallel cuts simultaneously having, in combination, a support, a frame pivotally mounted thereon, a shaft rotatably mounted in the frame, a cutter mounted on the end of said shaft, means normally tending to rotate said frame on its pivotal mounting to move the cutter away from the support and the work, a second shaft mounted in said frame parallel to the first shaft, and means carried by the second shaft and engaging with the first shaft to yieldingly force said frame and cutter toward the support and the work.

6. A clamp to secure a cutting apparatus to a pipe comprising, a body member, clamps, pivotally mounted one at each side of the lower end of the body member, a clamp screw rotatably mounted at the upper end of the body member and extending through each clamp, a nut on each clamp associated with the clamp screws for providing a straight pull in any angular position of the clamp, and means for rotating said clamp screws.

7. A machine of the class described adapted for forming parallel cuts simultaneously having, in combination, a guideway, supporting means at each end of said guideway, a support on said guideway, means for moving the support to and fro on the guideway, a pivotally mounted frame on each side of the support, a cutter rotatably mounted in each support, gears for transmitting power to rotate the cutters, and casings associated with each frame for enclosing said gears and preventing injury thereto and thereby.

8. A clamp to secure a cutting apparatus to a pipe comprising, a body member, clamps pivotally mounted, one at each side of the lower end of the body member, a clamp screw rotatably mounted at the upper end of the body member and extending

through each clamp, a nut on each clamp associated with the clamp screws, an angular member pivotally mounted in the clamp and engaging, one arm with the clamp and the other arm with the nut, whereby a relative movement of the clamp and screw is provided.

9. A machine of the class described adapted for forming parallel cuts simultaneously having, in combination, a pair of cutters, means associated therewith for limiting the depth of cut in accordance with the diameter of the pipe worked on, and clamping jaws cooperating with said means to position pipes of various diameters in proper relation with the cutters.

10. A machine of the class described adapted for forming parallel cuts simultaneously having, in combination, a pair of cutters, means associated therewith for limiting the depth of cut in accordance with the diameter of the pipe worked on, and means for positioning pipes of various diameters to cut therefrom a section of predetermined size.

11. A machine of the class described adapted for forming parallel cuts simultaneously having, in combination, a pair of cutters, means associated therewith for varying the depth of cut made in accordance with the diameter of the pipe being worked upon.

12. A machine of the class described adapted for forming parallel cuts simultaneously having, in combination, a pair of cutters, rotating washers associated therewith to vary the depth of cut made in accordance with the various diameters of pipe worked upon.

13. In a machine of the class described, the combination of a frame, a cutter mounted thereon, clamping jaws for positioning said frame on pipes of various diameters in predetermined relation with the cutter, and means associated with the cutter for varying the depth of cut in accordance with the diameter of pipe being worked upon.

14. In a machine of the class described, the combination of a frame, a cutter mounted thereon, clamping jaws for positioning said frame on pipes of various diameters in predetermined relation with the cutter, and means associated with the cutter and engaging with the outside of the pipe to vary the depth of cut in accordance with the diameter of pipe being worked upon.

In testimony whereof, I have signed my name to this specification, in the presence of two subscribing witnesses.

ARCHIBALD T. SAMPSON.

Witnesses:

JAMES R. HODDER,
HAROLD J. CLARK.
